US0D1005652S

(12) **United States Design Patent** (10) Patent No.: **US D1,005,652 S**
(45) Date of Patent: ** Nov. 28, 2023

(54) **SANDAL**

(71) Applicant: **Birkenstock IP GmbH**, Linz am Rhein (DE)

(72) Inventor: **Jerry Manuel**, Los Angeles, CA (US)

(**) Term: **15 Years**

(21) Appl. No.: **35/515,155**

(22) Filed: **Sep. 1, 2022**

(80) **Hague Agreement Data**

Int. Filing Date: **Sep. 1, 2022**

Int. Reg. No.: **DM/223278**

Int. Reg. Date: **Sep. 1, 2022**

Int. Reg. Pub. Date: **Sep. 16, 2022**

(30) **Foreign Application Priority Data**

Mar. 1, 2022 (EM) 008874754-0002
Mar. 1, 2022 (EM) 008874754-0004

(51) **LOC (14) Cl.** **02-04**

(52) **U.S. Cl.**

USPC **D2/916**; D2/919; D2/969

(58) **Field of Classification Search**

(74) Attorney, Agent, or Firm — Fross, Zelnick, Lehrman & Zissu, P.C.; Charles T. J. Weigell, Esq.

(57) **CLAIM**

The ornamental design for a sandal, as shown and described.

DESCRIPTION

1. Sandal
2. Sandal
- 1.1: Bottom
- 1.2: Front
- 1.3: Back
- 1.4: Perspective
- 1.5: Left
- 1.6: Right
- 1.7: Top
- 2.1: Bottom
- 2.2: Back
- 2.3: Left
- 2.4: Front
- 2.5: Right
- 2.6: Perspective
- 2.7: Top

The broken lines show portions of the invention that form no part of the claimed design.

1 Claim, 14 Drawing Sheets
